EXPANDING SHOE MECHANISM

Harold Bertram Mead, Ilford, England

Application June 2, 1938, Serial No. 211,429
In Great Britain June 3, 1937

10 Claims. (Cl. 188—78)

This invention relates to expanding shoe mechanism particularly for brakes, primarily but not exclusively for road vehicles, of the kind wherein the brake shoes are movably mounted on a base member and are expanded to engage the surrounding drum by means of a cam mounted for rotation between their free ends. The mechanism is applicable also to automatic clutches.

The object of the invention is to bring about automatically an increased frictional grip between shoes and drum by servo action in proportion to the resistance offered by the drum. For example, in a brake, the braking effort is automatically increased, and in a clutch the pressure of application is automatically increased.

According to the invention, an expanding shoe mechanism comprises a drum, a plurality of shoes movably mounted on a floating base member and disposed inside the drum for frictional engagement therewith, a cam rotatably mounted on the base member for expanding the shoes, an anchor plate on which the floating base member is mounted to rock around the axis of the brake against spring resistance, an auxiliary cam for increasing the expansion of the shoes, and a connection between said auxiliary cam and anchor plate whereby angular displacement between the floating base member and anchor plate turns the auxiliary cam.

Some embodiments of the invention will be described by way of example with the aid of the accompanying drawings, wherein:

Figure 1 is a front elevation of a brake showing a portion of the drum removed on the section line I—I of Figure 2;

Figure 2 is a transverse vertical section through the middle of Figure 1 (showing cams and link, referred to later, in full);

Figure 3 is a rear face view according to Figure 1;

Figures 4 and 5 are views similar to Figures 1 and 2 but of a modified arrangement the section of Figure 4 being on IV—IV of Figure 5;

Figure 6 is a front elevation of an automatic clutch showing a portion of the drum removed on the section line VI—VI of Figure 7; and

Figure 7 is a transverse vertical section through the middle of Figure 6 (showing the cams, links, and centrifugal weights, referred to later, in full).

Referring to the drawings in general, the drum is designated 1 and the shoes 2; the latter are movably mounted (pivotally at 3 in Figures 1—5, and slidably in Figures 6—7) on the floating base member 4 and, as usual, are disposed inside the

drum for frictional engagement with the inner cylindrical surface when they are expanded by a main cam or cams 5 rotatably mounted on the floating member 4. An anchor plate is designated 6, and the floating plate 4 can rock around the axis of the drum with respect to the anchor plate 6 against the resistance of springs 14.

In a convenient embodiment as shown in Figures 1—3 the auxiliary cam 7 is mounted or formed on a short link 8 rockable on pin 9 carried by the fixed anchor plate 6 which is coaxial with and adjacent to the floating base member 4. The main cam 5 is fast with its axle 10 which is mounted for rotation in the floating plate 4 and the edge of the anchor plate is clear of this axle 10 as shown, or may have an arcuate slot through which the main cam axle 10 passes. The axle carries at its end projecting from the anchor plate a cam operating arm 11, which is connected in any suitable manner to brake levers and/or 20 pedals. The axle is free to perform angular movement around the brake axis together with the floating plate 4. The auxiliary cam 7 is loose on the main cam axle 10 and in this embodiment is located between the main cam 5 and the floating plate 4. This relative disposition of cams 5 and 7 is reversed in Figures 4 and 5. The pivot 9 for the link 8 carrying the auxiliary cam 7 is fixed in the anchor plate 6 and passes through an arcuate slot 12 in the floating plate 4 and the 30 link is formed with an elongated hole 13 whereby it is loosely seated on the pivot 9.

The pivot 3 for the brake shoes is fixed in the floating plate 4 and is also clear of the anchor plate 6.

Any suitable spring arrangement may be provided for resisting angular movement of the floating plate 4. In Figures 2, 3 and 5 will be seen a pair of springs 14 anchored to the floating plate by one of the respective ends at 15, and to the anchor plate 6 through the medium of pivoted arms 16 mounted thereon. These arms 16 may be pulled against their respective stops 17 according to the direction of rotation of the member 4 in relation to the anchor plate 6. This 45 will put one of the springs under tension to resist the relative movement of members 4 and 6, whilst the other spring and its arm 16 rides free in the compression direction.

In operation, when the brake shoes 2 are applied to the drum 1 by means of the main cam 5 the floating plate 4 becomes connected to the drum through the main cam axle 10. If the momentum of the drum is sufficient to overcome the resisting action of the respective spring 14 55

retaining the floating plate same will be caused to perform angular movement and the floating plate will cause the main cam axle 10 to be angularly displaced around the brake axis. The auxiliary cam 7 being loosely mounted on the main cam axle 10 the latter will cause it to rock therearound, owing to the pin and slot connection 9-13 of the auxiliary cam carrying link 8 with the anchor plate 6. Thus the auxiliary cam 7 will further expand the brake shoes in proportion to the resistance of the drum to braking, the momentum of the brake drum being utilised for automatically increasing the braking effort; this action is illustrated in broken lines where the cam centres move to the angle indicated by the line A-B.

In Figures 4 and 5 there is shown a modification wherein the chief difference is that the link 18 (equivalent to the link 8 of the previous embodiment) is located outside the drum, and on the other side of the anchor plate 6. The auxiliary cam 7 is fast on a spindle 19 which passes through the hollow axle 20 of the main cam 5. When there is relative movement between the floating plate 4 and the anchor plate 6, as in the previous example, the spindle 19 is caused to turn (and consequently the cam 7) through the medium of the crank arm 21 which is pivoted to the link 18. This position is shown in dotted lines in Figure 4, the cam centres having moved through an angle bringing them on to the line A-B. Corresponding numerals of reference are given to other parts corresponding in the other figures.

The applicability of the invention to an automatic clutch is seen in Figures 6 and 7. The anchor plate 6 may be assumed to be fixed to a driving shaft 22, and the drum 1 to a driven shaft 23. In this case the shoes 2 are applied to the drum when they are expanded by the main cams 5 under the action of the weighted arms 24, these arms and their weights 25 flying out centrifugally to rotate the cam axles when the mass inside the drum is rotated anti-clockwise. It is to be understood that the anchor plate 6 and floating plate 4 are resiliently connected together by springs or the like, e. g. as shown at 14, 16, 17 in the previous embodiments, these springs not appearing in the sectional view Figure 7. Consequently rotation of the shaft 22 turns the plates 4 and 6, and devices carried thereby, en bloc causing the shoes to expand as described above. Then, as the resistance of the drum is encountered, the floating plate 4 lags relatively to the plate 6, and through the links 18, crank arms 19 and auxiliary cams 7, the shoes are further expanded, augmenting the pressure of application between the clutch elements (i. e. shoes and drum respectively). It will be observed that the members 18, 19, 7 operate as in the brake design of Figures 4 and 5, and are duplicated, as it is preferred to expand the shoes from diametrically opposite points, the shoes 2 sliding on pin-and-slot supports 26.

I claim:

1. An expanding shoe mechanism comprising a drum, a plurality of shoes movably mounted on a floating base member and disposed inside the drum for frictional engagement therewith, a cam rotatably mounted on the base member for expanding the shoes, an anchor plate on which the floating base member is mounted to rock around the axis of the brake against the spring resistance, an auxiliary cam for increasing the expansion of the shoes, and a link pivoted on the anchor plate

by a pin-and-slot connection, the pin passing through an arcuate slot in the floating plate, said link carrying the auxiliary cam, whereby angular displacement between the floating base member and the anchor plate rocks the link about its pivotal connection and turns the auxiliary cam. 5

2. An expanding shoe mechanism comprising a drum, a plurality of shoes movably mounted on a floating base member and disposed inside the drum for frictional engagement therewith, a cam rotatably mounted on the base member for expanding the shoes, an anchor plate on which the floating base member is mounted to rock around the axis of the brake against spring resistance, an auxiliary cam for increasing the expansion of the shoes, said auxiliary cam being carried by a spindle passing through a hollow axle revolvable in the floating base plate, the axle being rotatable manually by a cam operating arm, and the spindle by a crank arm fixed thereto and pivoted to a link pivotally mounted on the anchor plate, whereby angular displacement between the floating base member and anchor plate rocks the said link and crank arm and turns the auxiliary cam. 10 15 20

3. An expanding shoe mechanism comprising a drum, a plurality of shoes movably mounted on a floating base member and disposed inside the drum for frictional engagement therewith, a main cam rotatably mounted on the base member for expanding the shoes, an anchor plate with respect to which the floating base member is mounted to rock around the axis of the brake against spring resistance, an auxiliary cam for increasing the expansion of the shoes, the main cam being rotatable through centrifugal means, 25 and a connection between said auxiliary cam and anchor plate whereby angular displacement between the floating base member and anchor plate turns the auxiliary cam. 30 35

4. An expanding shoe mechanism, comprising, a drum, shoes within the drum, an anchor member, a floating base member carrying the expanding shoes and mounted to rotate relatively to said anchor member about an axis concentric with the drum against which the shoes expand, a main cam adapted to expand the shoes, an auxiliary cam mounted co-axially with the main cam, means operated by movement of the floating base relatively to the anchor member and operating the auxiliary cam to assist the main cam, and spring means arranged to control the relative movement between the floating base and the anchor member and tending to return the floating base to a position in which the auxiliary cam releases the shoes. 40 45 50 55

5. An expanding shoe mechanism, comprising, a drum, an anchor plate and a base member all mounted in co-axial relation, said base member being supported to rock relative to the anchor plate; a plurality of shoes movably supported on the base member and disposed inside the drum for frictional engagement therewith, a main cam rockably mounted on the base member for expanding the shoes, an auxiliary cam mounted co-axially with the main cam on the base member for increasing the expansion of the shoes, a connection between said auxiliary cam and anchor plate whereby angular displacement between the floating base member and the anchor plate turns the auxiliary cam, and means for normally and yieldingly holding the base member in fixed relation to the anchor plate. 60 65 70 75

6. An expanding shoe mechanism, comprising, a drum, an anchor plate and a base member all mounted in co-axial relation, and said base mem- 75

ber supported to rock relative to the anchor member, a plurality of shoes movably supported on the base member and within the drum for frictional engagement therewith, juxtaposed main and auxiliary cams co-axially mounted on the base member for expanding the shoes, an operating arm for actuating the main cam, and link means for operatively connecting the auxiliary cam with the anchor plate, said link means being located exteriorly of the drum.

7. An expanding shoe mechanism, comprising, a drum, an anchor plate and a base member all mounted in co-axial relation, and said base member being supported to rock relative to the anchor member, a plurality of shoes movably mounted on the base member and disposed inside the drum for frictional engagement therewith, main and auxiliary cams for expanding the shoes, said main cam being mounted on a tubular axle mounted to rotate in the floating base member and said auxiliary cam being mounted on a spindle arranged co-axially within said tubular axle, an operating connection for said tubular axle, link means for connecting the spindle of the main cam with the anchor plate, and spring means arranged to control the relative movement between the floating base and the anchor plate and tending to return the floating base to a position in which the auxiliary cam releases the shoes.

8. An expanding shoe mechanism, comprising, a drum, an anchor plate and a base member all mounted in co-axial relation, and said base member being supported to rock relative to the anchor member, a plurality of shoes movably mounted on the base member and disposed inside the drum for frictional engagement therewith, main and auxiliary cams for expanding the shoes, said main cam being mounted on a tubular axle mounted to rotate in the floating base member and said auxiliary cam being mounted on a spindle arranged co-axially within said tubular axle, an operating connection for said tubular axle, link means for connecting the spindle of the main cam with the anchor plate,

spaced abutments on the outer face of the anchor plate, arms pivoted at one end to the anchor plate, and springs having their outer ends connected to the free ends of said arms and their inner ends connected to a portion of the floating base member, said springs controlling the relative movement between the floating base and the anchor plate and tending to return the floating base to a position in which the auxiliary cam releases the shoes.

9. An expanding shoe mechanism, comprising, a drum, an anchor plate and a base member all mounted in co-axial relation, said base member having a slot and being supported to rock relative to the anchor plate, a plurality of shoes movably supported on the base member and disposed inside the drum for frictional engagement therewith, a spindle carried by the base member, a main cam rockably mounted on the spindle for expanding the shoes, an auxiliary cam loosely mounted on said spindle co-axially with the main cam for increasing the expansion of the shoes, a pivot pin carried by the anchor plate and projecting through the slot in the base member, a link carried with said auxiliary cam and having a slot receiving said pivot pin on the anchor plate whereby angular displacement between the floating base member and the anchor plate turns the auxiliary cam and means for normally and yieldingly holding the base member in a fixed relation to the anchor plate.

10. An expanding shoe mechanism, comprising, a drum, expanding shoes, an anchor member and a base member all mounted in co-axial relation, co-axially mounted main and auxiliary cams for successively expanding said shoes against the drum, means for mounting said cams for independent movement; pendulum means operated by centrifugal force, connected with and controlling the operation of the main cam; and a connection between said auxiliary cam and the anchor member, whereby angular displacement between the floating base member and the anchor member turns the auxiliary cam.

HAROLD BERTRAM MEAD. 45
